Act

UNITED STATES PATENT OFFICE.

FRANK PINK, OF PORTSMOUTH, AND JOHN PAXTON PETTY, OF READING, ENGLAND.

TEMPORARY BINDER OR LOOSE-SHEET HOLDER.

No. 909,331.

Specification of Letters Patent.

Patented Jan. 12, 1909.

Application filed June 13, 1908. Serial No. 428,285.

To all whom it may concern:

Be it known that we, FRANK PINK and JOHN PAXTON PETTY, subjects of His Majesty the King of Great Britain, and residing at 5 114 Commercial road, Portsmouth, Hampshire, England, and 104 Kendrick road, Reading, Berkshire, England, respectively, have invented new and useful improvements in Temporary Binders or Loose-Sheet Holders, of which the following is a specification.

This invention relates to improvements in temporary binders or loose sheet holders in which the sheets, as is now well known, are securely but detachably retained between 15 clamping parts of the binders or holders so that any particular sheet or sheets can be readily removed or a new sheet or sheets inserted, the sheets being provided with slotted holes or openings for permitting engagement 20 therewith of posts, cords, thongs, or bands provided in connection with the binders or holders for the purpose of preventing unintentional displacement or detachment of the sheets when the clamping parts or bars are 25 drawn apart.

The principal object of the present invention is, in a temporary binder or loose sheet holder whereof the clamping parts are drawn together by winding up or drawing out one or 30 more flexible connections which is or are attached to both clamping parts to provide for engaging the loose sheets and maintaining these neatly and in proper position all in register in the binder, means separate from the 35 flexible connections serving to pull the clamping parts together, as we have found by extended experiments that it is practically impossible to maintain the sheets neatly in register by fastening these upon the said 40 flexible connections, and relying upon the latter only, to keep the sheets exactly over each other at all times.

For this purpose our invention consists in providing the binder with two or more 45 leather straps or the like, *e. g.*, flexible thongs of suitable material, which being secured at one end are passed through openings in the two clamping parts of the binder and then into one of the covers proper, which is made 50 hollow for the purpose, and in which the other ends of the flexible thongs are left quite free. In this way, we are able to provide far more relatively rigid means for engaging the slotted openings in the loose sheets 55 than can be provided by the said flexible connections of the clamping parts, owing to the

function of such flexible connections in their co-operative relation with the means, such as a screwed rod and nut, for drawing the clamping parts together. 60

To make our invention clearly and readily understood, we will describe the same with reference to a form of binder in which the clamping parts are drawn together by a flexible length of webbing, etc. tightened by a 65 nut and screw device. A binder of this kind is shown in the accompanying drawings with our improved sheet engaging means embodied therein, Figure 1 being a perspective view of the binder; Fig. 2 a sectional view of 70 the clamping bars; Fig. 3 a transverse section taken upon the line x x Fig. 2; Fig. 4 a partial front view of the clamping bars; Fig. 5 a vertical section of the binder; Fig. 6 a rear view of the binder, and Fig. 7 a view of a corner of 75 one of the sheets showing the openings for engaging the flexible thongs and for providing a passage for the flexible connections.

The binder shown consists of clamping bars *a* and *b* formed of channel or trough section and terminating in end walls *c*, *c* and provided with removably connected cover-plates *d*. The end walls *c*, *c* of the clamping bar *a* (hereinafter termed the upper clamping bar) form bearings for a threaded shaft *e* 80 which is mounted in the bar *a* and has threaded thereon a block or slide *f* fitted within the said bar *a* so that upon the rotation of the shaft *e* it will move longitudinally of the bar according to the direction of rotation of the shaft. To this block or slide *f* in the example illustrated are connected the ends of a length of tape, webbing, leather strap, chain, wire, cat-gut, or equivalent 85 flexible length or strip *f*', which as shown 90 passes straight out along the bar *a* over an anti-friction roller *g*, through oppositely situated slots *h*, *h*' formed in the cover-plates *d* towards the ends of the bars *a* and *b*, then over anti-friction rollers *i*, *i* in the bar *b*, 100 through oppositely situated slots *h*², *h*³ formed in the cover plates towards the other ends of the two bars, over an anti-friction roller *j* and straight out along the bar *a* round an anti-friction roller *g*', located adjacent to the 105 roller *g*, back to the slide or block *f*. With such an arrangement, which we are aware has already become known and therefore is not, *per se*, claimed by us, it will be seen how by rotating the threaded shaft *e* as by means of 110 a key in a right hand direction, the slide or block *f* will be moved to the left (Fig. 2) and

will draw the tape or webbing or equivalent length f^1 straight out along, or longitudinally of the bar a , thereby shortening the distance between the rollers g , i and j , i and so pulling the clamping bars a and b towards each other until the sheet or sheets placed between the bars are securely gripped therebetween. When however it is desired to insert or remove a sheet or sheets, a reverse rotation of the shaft e will cause the slide or block f to be moved along to the right (Fig. 2) and thereby allow the bars a and b to be retracted one from the other a distance corresponding to the decrease in the distance between the slide or block f and the rollers g , g^1 . Now according to our invention we do not fasten the sheets upon those parts of the tape, webbing, or equivalent f^1 which extend from one clamping bar to the other, but provide separate means consisting of flexible thongs secured at one end only for this purpose. As shown in Fig. 5 we provide two or more leather straps or the like k which may conveniently be connected to the lower cover proper l which is hinged to the bar b , the straps or the like passing up through slots m and n in the lower clamping bar b and cover-plate d respectively, and slots o and p in the cover-plate d and upper clamping bar a respectively, into the upper hollow cover proper l^1 , hinged to the bar a , by way of openings l^2 formed in the frame thereof, the straps or the like working quite free in the cover proper l^1 as the upper clamping bar is raised or lowered relative to the lower clamping bar. In this way it will be obvious how we are able to provide a far more relatively rigid holding of the sheets than is possible with the flexible connections of the clamping parts, and consequently in a binder according to our invention the sheets are held exactly over each other at all times.

Fig. 7 illustrates part of a sheet adapted by slots or openings such as q to be engaged by the straps or the like k , and by slots or openings such as r to provide clearance for the tape, webbing, or equivalent f^1 as this passes from one bar to the other. It is not however essential that the tape or the like f^1 passes through the sheets as in the example shown. This or these may pass from one bar to the other clear of the rear edges of the sheets if desired.

From the foregoing it will be clear that the essential point of our invention lies in the loose ended flexible thongs constituting means, separate from the flexible connections of the clamping parts, for engaging and holding the loose sheets in such manner that at all times they are maintained exactly over each other or in register.

We may in constructing the binder detachably connect the flexible connectors to

the "lower" clamping bar, so that when the connectors have been slightly slackened by rotation of the threaded shaft in the proper direction, they may be detached from the "lower" clamping bar so as to allow the "upper" clamping bar and cover proper to be instantly raised to any desired height. To re-secure the binder again all that would be necessary would be to replace the clamping bar and cover proper against the sheets, re-attach the connectors and tighten up these to draw the clamping bars together.

In some cases, the binders may be constructed with the covers arranged separate and distinct from the clamping parts so as to be secured therebetween in similar manner to the sheets themselves, or in lieu of the covering for the clamping bars and the covers forming the hinge connection therebetween as shown, we may find it more convenient to hinge the covers proper to the clamping bars in other ways, for instance, we may pivotally connect extensions or hinge pieces of the covers proper to the clamping bars.

Having thus described our invention, what we claim as new and desire to secure by Letters Patent is:—

1. A temporary binder, comprising in combination clamping bars, a hinged cover appropriated to each clamping bar, engaging and register-maintaining means for the sheets consisting of flexible lengths engaging openings in the sheets, and having one end fixed to one of the covers and the other end free, and extending through both clamping bars, said free end passing loosely into the other cover, and means for drawing the clamping bars together to grip and hold the sheets securely therebetween without hindrance to the opening and closing of the covers substantially as herein described.

2. A temporary binder, comprising in combination clamping bars, a hinged cover appropriated to each clamping bar, engaging and register-maintaining means for the sheets consisting of flexible lengths engaging openings in the sheets and having one end fixed to one of the covers and the other end free, and extending through both clamping bars and loosely into the other cover, a flexible connector connecting the clamping bars, and means for tightening the connector to draw the clamping bars together.

In testimony whereof we have signed our names to this specification in the presence of two subscribing witnesses.

FRANK PINK.
